DIRECTIVE BROAD BAND SLOT ANTENNA SYSTEM

Victor H. Rumsey, Montreal, Quebec, Canada,
assignor to Minister of Supply in His Majesty's
Government of the United Kingdom of Great
Britain and Northern Ireland, London, England

Application June 5, 1946, Serial No. 674,437

4 Claims. (Cl. 250—33.63)

1

This invention relates to antennas; in particular it is directed to providing a directive antenna array possessing electrical stability and substantially uniform characteristics over a wide band of frequencies.

Antenna arrays normally comprise a plurality of substantially identical primary radiators oriented relative to one another according to a predetermined pattern. The primary radiators are excited by radio frequency energy fed to the individual radiators by a suitable feeder system. In some cases all the primary radiators in an array are excited by currents or fields which are uniform in magnitude and time phase. Often, on the other hand, array design requires a non-uniform distribution of energy among the various primary radiators, or progressive change of time phase from one primary radiator to another. Conventional primary radiators, assembled in an array, are often difficult to excite according to a predetermined pattern of energy and phase distribution because of complications resulting from mutual electromagnetic coupling between radiators within the array. An object of this invention is to provide an array wherein mutual electromagnetic coupling between primary radiators is negligible.

A frequent requirement for antennas to be used in modern high-frequency applications is that the system possess substantially uniform radiation characteristics and input impedance over a relatively broad band of frequencies, percentage wise. It is accordingly another object of this invention to provide an array which may be made to give substantially uniform performance over a frequency band which may equal as much as twenty percent of the center frequency for which the system is designed.

A further object of this invention is to provide an antenna operative to radiate electromagnetic fields which are uniformly polarized in a desired plane.

The basic principle of the components of the invention is that an opening in a conducting surface, i. e., a slot, possesses radiating properties closely analogous to those of a dipole, with the important qualification that the spatial orientation of the electric and magnetic fields produced by a slot is at right angles to the orientation of the respective fields produced by a similarly situated dipole. Thus, whereas a horizontal dipole produces a wave wherein the electric field vector is polarized horizontally, a horizontal slot produces a wave having the electric field vector vertically polarized. From this fact it follows that an array for producing vertically polarized

2

waves concentrated in a narrow beam in the horizontal plane can be made up of a plurality of horizontal slots placed end to end and separated one from another by conducting surfaces. The individual radiating slots in such an array are almost perfectly isolated from one another, electromagnetically speaking, and mutual coupling is negligible. An array of dipoles operative to produce a similarly polarized beam in the horizontal plane must comprise a plurality of substantially parallel vertical dipoles. The tendency to mutual coupling between such dipoles is very strong, and shielding one from another is difficult.

The particular embodiment of this invention which is herein shown and described is an array constructed according to the slot principle and incorporating certain additional novel features which contribute to more effective operation. The detailed description of this embodiment of the invention will be made with reference to the appended drawings, of which:

Figure 1 is a showing in perspective of an illustrative array comprising four slot radiators, oriented end to end;

Figure 2 is a schematic representation of the array of Figure 1, together with a feeder system, showing how the energy distribution among the component radiators of the array might be tapered according to some predetermined formula;

Figure 3 shows in larger scale, in perspective, one of the slot radiators from the array of Figure 1; and

Figure 4, in cross section, shows constructional details of the slot radiator illustrated in Figure 3.

By referring to Figure 1 it may be seen that the array illustrated therein consists of four slot radiators, those to the left of the array center being denoted 11 and 12, and those to the right being denoted 21 and 22 respectively. In this embodiment each slot radiator has an aperture approximately one wavelength long. Figure 1 does not show details of assembly; those are illustrated more fully in Figures 3 and 4. Figure 1 does, however, show the general constructional features. A base plate 101, a back plate 122, and a top plate 121 run the entire length of the array and are, in this embodiment, integrally formed from a single piece of conducting material. A plurality of end plates 102, formed of conducting material, serve as partitions to form, in conjunction with plates 101, 121, and 122, a series of open-faced rectangular boxes. Slot radiators 11, 12, 21, and 22 consist respectively of the open faces of said rectangular boxes. Base plate 101 extends a substantial distance

in front of the radiating slots 11, 12, 21, and 22, and is terminated by an extension 104 which is bent sharply backward to form an acute angle with the principal portion of base plate 101. This extension 104 functions as a choke to minimize radiation in the backward direction from the array. Another such choke is formed by an extension 103 on top plate 121. This extension rises vertically directly above the radiating apertures or slots and is bent sharply backward at its extremity as shown in Figure 1. The function of this choke is also to prevent back radiation.

The slot radiators which make up the array are supplied with radio frequency energy by currents fed to quarter-wave antennas 105, one of which is oriented vertically on the midline of each slot (Fig. 2). Antennas 105 and other features of the individual slot radiators will be discussed in a subsequent paragraph with reference to Figures 3 and 4.

Figure 2 shows schematically how the array of Figure 1 might be driven from a single source were it desired to supply energy non-uniformly to the various radiators. The radiators of the array in Figure 1 are represented by boxes having the same designating numerals as the corresponding radiators. Solid lines in Figure 2 represent transmission lines. Figure 2 illustrates a feeder system appropriate to supply currents in uniform time phase to all four radiators, with equal currents of one magnitude being fed to radiators 11 and 21, and equal currents of a different magnitude being fed to radiators 12 and 22. Transmission lines from radiators 11 and 12 are joined to the respective branches of a T-junction 17. In the line running to radiator 12 an impedance transformer 13 is inserted; this transformer may be of the well-known quarter-wave-section type; its purpose is to make the ratio of impedances appearing at the two legs of T-junction 17 appropriate to effect the desired division of power between radiator 11 and radiator 12. Transmission lines likewise join radiators 21 and 22 to the respective branches of a T-junction 18, and an impedance transformer 14, identical to transformer 13, is inserted in the line running to radiator 22.

The stems of T-junctions 17 and 18 are connected by transmission lines to the respective branches of a third T-junction, designated 16 on the drawing. The stem of junction 16 is connected through an impedance transformer 15 to a line coming from the radio transmitter (not shown). The lengths of the various segments of transmission line may be proportioned so that the total lengths of the feed paths from T-junction 16 to each of the radiators are equal. This will insure that the currents fed to the various radiators will have identical time phase. If it be desired to feed the radiators with currents whose phases mutually differ, the lengths of the feed lines to the radiators may be adjusted in appropriate manner to achieve the required phase relation among the various feed currents.

A simple feed system of the sort just described may be readily designed for use with this invention, because, as will be more fully set forth later, the primary radiators in the array can be designed to have substantially constant input impedance over a wide band of frequencies, independently of the excitation which may be supplied to neighboring radiators. To state the point differently, the absence of mutual coupling among the radiators of this array greatly sim-

plifies the design of a feeder to supply currents of arbitrarily chosen phases and magnitudes to the various radiators.

In Figure 3 a single slot radiator is shown in perspective. Observe that the slot or open radiating area is bisected by a vertical strut 107, formed of conducting material. As has been heretofore stated, the radiating slot in this embodiment of the invention is about one wavelength long, and the radiation emanating from the slot has vertical electric field polarization. The presence of strut 107, joining the base plate 101 and the top plate 121 at the midline of the slot, insures the presence of an electric field null at the middle of the slot and thereby compels the slot to operate in the proper mode, with a half-wavelength electric field configuration between one end plate and the strut and another such configuration between the strut and the opposite end plate. This strut has been found particularly useful in achieving substantial uniformity of directive pattern over a band of operating frequencies.

The antenna 105, which provides electromagnetic excitation of the radiating slot, is located midway between end plates 102, about a quarter-wavelength in front of back plate 122. Antenna 105 is a relatively thick conducting tube about a quarter-wavelength long, mounted on a supporting insulator 106. A suitable coupling for connecting a feeder to antenna 105 is provided on the underside of base plate 101; it is shown in Figure 4 and will be described with reference to that drawing.

A pair of small parasitic radiators 108 are mounted on base plate 101, symmetrically with respect to strut 107. They are situated slightly posterior to the open radiating slot and about midway between the strut and the end plates. Each parasitic radiator consists of a short metallic upright, conductively mounted on the base plate. Parasitic elements 108 perform a novel and important function which will be described in a subsequent paragraph.

Figure 4 is a cross-section view of the radiator of Figure 3, the section being taken in the plane passing through the midline of strut 107 and the axis of antenna 105. Referring to Figure 4, note that a tubular coupling 113, externally threaded and having a flange around the upper portion thereof, is fitted into a circular aperture in base plate 101 and held securely in place by a circular nut 114. Resting on coupling 113 is insulator 106, which comprises a disk of insulating material having a raised extension coaxial with the main disk but smaller in diameter. Insulator 106 has a central aperture concentric with the aperture in coupling 113 but substantially smaller in diameter. Insulator 106 is held rigidly in position over coupling 113 by means of machine screws 111, by which insulator 106 is bolted to base plate 101.

Antenna 105 consists of a length of hollow tubing made of conducting material; its outer diameter is substantially equal to the diameter of the raised portion 120 of insulator 106, on which it rests. The inner diameter of antenna 105 is substantially greater than that of the central aperture in insulator 106. An insulating sleeve 119, having outer diameter proportional to fit snugly within antenna 105 and inner diameter equal to that of the aperture in insulator 106, is fitted within the lower portion of antenna 105 so as to rest upon the upper surface of extension 120.

The length of sleeve 119 is about one-third the overall length of antenna 105.

A conducting cylindrical rod 115, having an enlarged cylindrical head, passes through sleeve 119 and the aperture in insulator 106. The enlarged head of rod 115 is proportioned to fit snugly within antenna 105 and it is securely affixed thereto by set screws 118. The principal portion of rod 115 has diameter appropriate to cause it to fit snugly within sleeve 119 and the aperture in insulator 106. The length of rod 115 is such that its lower end extends beyond the insulator 106 to a point within and slightly above the lowest extension of coupling 113. A machine screw 116 passes transversely through raised extension 120 and rod 115, suitable machined apertures being provided therefor. Nut 117 secures screw 116 and thereby holds rod 115 rigidly in proper position.

Coupling 113, with rod 115 centered therein, affords a means for coupling an unbalanced coaxial transmission line to the radiator unit. Antenna 105, acting as a quarter wave radiator in conjunction with base plate 101, excites the slot radiator with radiant energy. All the energy radiated by the unit is directed through the slot aperture, since the side, back, top, and bottom plates reflect substantially all the radiation which impinges upon them.

The impedance presented to the transmission line feeding the radiator depends to a large extent upon reflections from the walls and from the slot itself. A match is obtained when all the reflections are so phased as to cancel the existing mismatch between the antenna and the line. Under those conditions the energy in the transmission line is wholly radiated from the slot, and no standing waves are present on the transmission line. The major portion of the energy from antenna 105 reaches the slot aperture after reflecting from the walls of the cavity or from strut 107, only a small fraction of the energy proceeding directly to the slots. This state of affairs would normally result in a system highly sensitive to the frequency changes; in this invention frequency sensitivity due to multiple reflections is prevented by means of the parasites 108, heretofore described.

The action of parasites 108 may best be explained by regarding the transmission from antenna 105 to the radiating slot as transmission along a short length of waveguide, consisting of the enclosed cavity formed by the top, bottom, back, and side plates. This waveguide is of course loaded by the slot itself, which serves as a means of effecting energy transfer with outside space. An overall match between the slot, the waveguide, the antenna and the feeder can be achieved for any one frequency by proper choice of the slot dimensions, the antenna dimensions and the distance separating the antenna from the back plate. By adding the parasitic radiators 108, however, a good match can be obtained over a wide band of frequencies because the parasites act as capacitive loading stubs providing shunt reactance across the waveguide. The reactance variation of the parasites as a function of frequency is opposite in sign to that of the system proper and thus tends to maintain an essentially resonant condition over a wide band of frequencies. The characteristics of the parasites depend upon their location and physical dimensions. In a practical construction it was found that by proper choice of stub shape, size and location, a good impedance match could

be obtained over a 20% frequency band and that moreover, the input resistance of the antenna 105 could be set at any desired value between 30 and 70 ohms. Thus the parasites 108 not only broaden the usable frequency band but make unnecessary any impedance matching device to couple antenna 105 to its transmission line. The construction just referred to was designed for a center frequency of 1000 mc./s., and the voltage standing wave ratio on the feeder did not exceed 1.3 to 1 at any frequency between 900 mc./s. and 1150 mc./s.

It will be understood that the embodiment of the invention herein shown and described is exemplary only, and that the scope of the invention is to be determined with reference to the appended claims.

What is claimed is:

1. A slot radiator comprising a conducting cavity substantially in the form of a rectangular box having a top, a base, and one open side forming the slot, a strut of conducting material bisecting the open side and extending between the top and base of the cavity to insure an electric field null at the center of the slot and preserve a uniform directivity pattern over a band of frequencies, an antenna substantially perpendicular to the base disposed within the cavity remote from the open face, feeder means coupled to the antenna, and a pair of capacity loading stubs much shorter than said strut and disposed parallel thereto, said stubs being mounted on the base on either side of the strut but within the cavity enclosure to provide a shunt reactance across the slot whose reactance variation as a function of frequency is opposite in sign to that of the cavity.

2. A slot radiator comprising a conducting cavity substantially in the form of a rectangular box having a top, a base, and one open side forming the slot, said open side measuring one wavelength at the center of the operating band in the dimension parallel to the top and the base, a strut of conducting material bisecting the open side and extending between the top and base of the cavity to insure an electric field null at the center of the slot and preserve a uniform directivity pattern over a band of frequencies, an antenna substantially perpendicular to the base disposed within the cavity remote from the open face, feeder means coupled to the antenna, and a pair of capacity loading stubs much shorter than said strut and disposed parallel thereto, said stubs being mounted on the base on either side of the strut but within the cavity enclosure to provide a shunt reactance across the slot whose reactive variation as a function of frequency is opposite in sign to that of the cavity.

3. A slot radiator comprising a conducting cavity substantially in the form of a rectangular box having a top, a base, and one open side forming the slot, said open side measuring one wavelength at the center of the operating band in the dimension parallel to the top and base of the cavity, a strut of conducting material bisecting the open side and extending between the top and base of the cavity to insure an electric field null at the center of the slot and preserve a uniform directivity pattern over a band of frequencies, an antenna substantially a quarter wavelength at the center of the operating band mounted perpendicular to the base and disposed within the cavity remote from the open face, feeder means coupled to the antenna, and a pair of capacity loading stubs much shorter than said strut and disposed

parallel thereto, said stubs being mounted on the base on either side of the strut but within the cavity enclosure to provide a shunt reactance across the slot whose reactance variation as a function of frequency is opposite in sign to that of the cavity.

4. An antenna array having a plurality of slot radiators formed from rectangular box-shaped conducting cavities disposed side by side comprising, three large conducting plates forming the top, the base, and the back respectively of all of said cavities, a plurality of smaller conducting plates forming side walls for said cavities, said smaller plates dividing adjacent cavities and with the top and base plates defining open front faces forming the slot for each cavity, each of said slots measuring one wavelength between the side walls at the center of the operating band, a strut of conducting material bisecting the open face of each of said cavities and extending between its top and its base to insure an electric field null at the center of the slot and preserve a uniform directivity pattern over a band of frequencies, an antenna a quarter wave in length at the center of the operating band vertically mounted on the base of each of said cavities and disposed within its respective cavity remote from the open face, feeder means coupled to each of said antennas, and a pair of capacity loading stubs for each of said cavities, said stubs being much shorter than their respective struts and disposed parallel there-

to, said pairs of stubs being mounted on the cavity base on either side of their respective strut but within the cavity enclosure to provide a shunt reactance across each slot whose reactance variation as a function of frequency is opposite in sign to that of the cavities.
